Herbert C. Ladd
HIS ATTORNEY

UNITED STATES PATENT OFFICE.

JOHN F. KIRGAN, OF PHILLIPSBURG, NEW JERSEY, ASSIGNOR TO INGERSOLL-RAND COMPANY, OF JERSEY CITY, NEW JERSEY, A CORPORATION OF NEW JERSEY.

LOW-LEVEL MULTIJET CONDENSER.

Application filed March 15, 1923. Serial No. 625,201.

To all whom it may concern:

Be it known that I, JOHN F. KIRGAN, a citizen of the United States, a resident of Phillipsburg, county of Warren, and State 5 of New Jersey, have invented a certain Low-Level Multijet Condenser, of which the following is a specification accompanied by drawings.

This invention relates to low level multi-10 jet condensers, but more particularly to a condenser having regulating means for the water jets and for the diffuser.

The objects of the invention are to enable 15 the flow of water through each jet to be regulated and controlled, and also to enable the diffuser to be controlled proportionately to the jets. The condenser is thus more efficient and more economical in its use of water.

20 Further objects of the invention will hereinafter appear and the invention is shown in one of its preferred forms in the accompanying drawings, in which—

Figure 1 is a longitudinal sectional elevation 25 of a condenser,

Figure 2 is a similar view partly broken away showing some of the parts in a different position, and

Figure 3 is a detail transverse sectional view on the line 3—3 of Figure 1, looking in the direction of the arrows.

Referring to the drawings, the condenser comprises a casing having the lower section or body A, the upper section or inlet head B, 35 the throat piece C, and diffuser casing D together forming the diffuser, and the tail pipe E which is adapted to be partially submerged as usual in the tank or sump (not shown). The diffuser is constructed with a contracted throat formed by the lining piece F in the entrance of the diffuser, which is also the outlet of the condenser casing. A water head G in the upper portion of the casing carries the nozzles H which direct jets 40 or streams of water convergently towards the throat of the diffuser, and the convergent streams of water may be surrounded by the combining tubes, J, between the vanes K of which the steam passes to the streams of 45 water in the usual manner. In this instance, the steam enters the casing at the steam inlet L at the top and the casing is provided with the man hole opening O. The usual vacuum breaker may be provided in 50 the casing P and as shown the ball Q is

adapted to be raised by water and break the vacuum within the casing. The vacuum breaker casing is connected to the inlet head B, as by means of the pipe R.

The nozzles H, as shown, are removably 60 mounted in the water head G, and each nozzle is provided with a regulating valve S by means of which the flow through the nozzles may be regulated and controlled. The stems of the valves S are sealed by the glands T and in accordance with my invention, all the nozzle regulating valves S are simultaneously adjustable. For this purpose, the valve stems are connected to a spider U and an adjusting rod V passing centrally 70 through the water head G has a screw threaded shank W to which the hub of the spider U is threaded. Means are provided for rotating the adjusting rod V and thus raising and lowering the spider U, which 75 adjusts the nozzle valves S away from and towards the outlets of the nozzles. For adjusting purposes the rod V has a beveled gear X at its upper end meshing with a beveled pinion Y on the spindle Z adapted to 80 be rotated by the crank disc a.

The adjusting rod V as shown, is threaded to a socket piece b on the stem c of a valve d which enters the diffuser. The valve d is preferably in the form of an 85 elongated member having longitudinal grooves e sliding on the guides f. When the adjusting rod V is rotated in one direction or the other for adjusting the nozzle valves S, the valve stem c and diffuser valve 90 d will be raised or lowered in accordance with the direction of rotation of the rod V. In Figure 2 for instance, the rod V has been rotated in a direction to cause the nozzle valves S to move inwardly towards the nozzle entrances, while at the same time the screw threaded end of the rod V has entered the socket piece b to a greater extent, thus raising the diffuser valve d further within the throat of the diffuser. Under such circumstances, as shown in Figure 2, less water 95 is discharged from the nozzles and a more restricted passage is at the same time provided through the diffuser.

I claim:

1. A low level multi-jet condenser, comprising a casing having a diffuser at its lower end and a contracted throat at the entrance of said diffuser, a water head in the upper portion of the casing and a ring of 110

nozzles on said head for directing converging streams of water to the said throat of the diffuser, each nozzle having an adjustable regulating valve.

5. 2. A low level multi-jet condenser, comprising a casing having a diffuser at its lower end and a contracted throat at the entrance of said diffuser, a water head in the upper portion of the casing, a ring of nozzles on said head for directing converging streams of water to the said throat of the diffuser, each nozzle having an adjustable regulating valve, and means for simultaneously adjusting all of said regulating valves.

10 15. 3. A low level multi-jet condenser, comprising a casing having a diffuser at its lower end and a contracted throat at the entrance of said diffuser, a water head in the upper portion of the casing, a ring of nozzles on said head for directing converging

20

streams of water to the said throat of the diffuser, each nozzle having an adjustable regulating valve, and an adjustable regulating valve for the diffuser.

4. A low level multi-jet condenser, comprising a casing having a diffuser at its lower end and a contracted throat at the entrance of said diffuser, a water head in the upper portion of the casing, a ring of nozzles on said head for directing converging streams of water to the said throat of the diffuser, each nozzle having an adjustable regulating valve, an adjustable regulating valve for the diffuser, and means for simultaneously adjusting all of said nozzle valves and the diffuser valve.

In testimony whereof I have signed this specification.

JOHN F. KIRGAN.
